COMBINED CAP, POURING SPOUT AND CAPTIVE
CLOSURE FOR A BOTTLE OR THE LIKE

William D. Williams, Toledo, Ohio, assignor to Lehn & Fink Products Corporation, New York, N.Y., a corporation of Delaware

Filed Nov. 30, 1965, Ser. No. 88,262

Term of patent 14 years

(Cl. D58—26)

FIG. 1

FIG. 2

FIG. 2 is a rear perspective view thereof;

FIG. 3 is a front elevational view on a larger scale showing the closure in open position; and

FIG. 4 is a bottom plan view thereof, also on a larger scale.

I claim:

The ornamental design for a combined cap, pouring spout and captive closure for a bottle or the like, substantially as shown.
